W. DALTON.
PROJECTILE FUSE.
APPLICATION FILED JULY 18, 1916.

1,208,104.

Patented Dec. 12, 1916.

UNITED STATES PATENT OFFICE.

WILLIAM DALTON, OF SCHENECTADY, NEW YORK.

PROJECTILE-FUSE.

1,208,104.

Specification of Letters Patent. Patented Dec. 12, 1916.

Application filed July 18, 1916. Serial No. 109,886.

To all whom it may concern:

Be it known that I, WILLIAM DALTON, of Schenectady, in the county of Schenectady and State of New York, have invented a certain new and useful Improvement in Projectile-Fuses, of which improvement the following is a specification.

My invention more particularly relates to explosive projectile fuses, in the operation of which a percussion element is caused to fire an explosive charge when the velocity of the projectile, while in flight, is retarded by any obstacle.

The objects of my invention are to provide a flash port in a percussion element, in order to avoid the cost of drilling a long port in the fuse body; to provide a simpler and more effective safety percussion element, which will guard against the accidental firing of the explosive charge, during the loading and transportation of the projectile; to provide a simpler form of fuse body, by eliminating a long tortuous port, in order to avoid losses from imperfect workmanship and porosity of the material; and to provide means for arming, and automatically disarming, the percussion element when the projectile rotates at a predetermined speed.

The improvement claimed is hereinafter fully set forth.

In the accompanying drawings: Figure 1 is an axial section through a well known type of projectile fuse, illustrating an embodiment of my invention; Fig. 2, a partial section, on a reduced scale, illustrating the firing position of my improved percussion element; and, Fig. 3, a detailed bottom view of the percussion element.

In the practice of my invention, referring descriptively to the specific embodiment thereof which is herein exemplified, the body, 1, of the fuse, carries the powder timing train rings, 2 and 3, which are fastened to the body by a closing cap, 4, in the usual manner. A concussion element, 5, which is inclosed by the cap, is adapted to fire the powder trains, 2^a and 3^a, at the instant the projectile starts from a gun. The base powder charge in the chamber, 6, is fired by the timing powder train, as usual, at the instant corresponding to the adjusted setting of the timing train ring, 3, if it has not been previously fired by the action of my improved percussion element to be hereinafter described. A closing screw, 8, provided with wrench sockets, 8^a, is screwed

against a seat, 1^b, on the body, to tightly close a centrally disposed percussion chamber 1^a, and the annular base charge powder chamber, 6, in the usual manner. A percussion spool, 7, the bore of which is adapted to contain a powder core, 7^c, is centrally disposed within the chamber, 1^a, and is supported and guided by a slotted cup, 9, so as to permit it to slide toward and from a firing pin, 14, which projects inwardly from the front end of the chamber.

The annular seat, 8^b, against which the spool, 7, abuts, is of ample size to resist crushing when suddenly accelerating and impelling the spool, at the instant the fuse is fired from a gun. A washer, 8^d, and a fiber disk, 8^e, form a partition between the charge of powder, 8^f, in the closing screw, and the spool, 7, a small intervening space being interposed, as illustrated. A disk, 8^g, closes the outer or back side of the screw, in the usual manner. The ports, 8^h, are of the usual form, and establish communication between the powder in the closing screw and the annular chamber, 6. The slotted cup, 9, which abuts against an annular seat, 1^s, formed on the front side of the chamber, 1^a, positions a plurality of centrifugal safety locking triggers, 10, which are loosely embraced by lateral slots, 9^b, formed in the cup. An inwardly projecting arm, 10^a, is formed on the front extremity of each of the triggers, the ends of said arms bearing on a spring washer, 11. A helical spring, 12, abuts against the washer, 11, and against a flange, 7^a, formed on the back end of the percussion spool, 7. The flange, 7^a, also provides a seat for the back or abutting ends of the triggers, when the percussion element is in its normally locked or disarmed position, as shown in Fig. 1. The cup also guides and centrally positions the spool, 7, and a threaded cup nut, 13, which is screwed upon the front end of the spool, 7, for the purpose of fastening a percussion detonator cap, 13^a, in such manner as to fairly strike the firing pin, 14, when the percussion spool, 7, moves forward to its firing position shown in Fig. 2. The cap fires the powder core, 7^c, and thereby ruptures the fiber disk, 7^t, which closes the back end of the spool. The fire-flash continues rearward, ruptures the disk, 8^e, and fires the base charge, 8^f, and the charge contained in the chamber, 6, and, with this added force, fires an explosive charge in the projectile, which is not shown,

as it may be of any of the known constructions.

The compressive force of the spring, 12, is so proportioned and transmitted to the triggers, 10, by the washer, 11, and the projecting arms, 10^a, as to provide a predetermined centripetal force. This force only permits an outward unlocking movement of the back ends of the triggers, which will 5 clear the flange, 7^a, and thereby arm the percussion element, at rotative speeds of the projectile above 2000 revolutions per minute, or such other predetermined speed of rotation as may be desired.

15 As illustrated in Fig. 1, in the practice of my invention, the percussion element is assembled in the chamber, 1^a, in its normally locked and disarmed position. It comprises the percussion spool, 7, with the detonator 20 cap, 13^a, fastened thereto by the cup nut, 13, and the triggers, 10, which are embraced by the slotted cup, 9, and are held in their inner positions by the washer, 11, which opposes the spring, 12. This spring also normally 25 positions the spool, with its attached parts, against the closing screw, 8, at a safe distance from the firing pin, 14, so as to permit the back ends of the triggers to abut against the flange, 7^a, of the spool, and thereby 30 lock it in the normal disarmed position shown.

The mass and form of the triggers are so proportioned, relatively to the centripetal force due to the compressive resilience of the spring, as to require, during the flight 35 of a projectile, a fuse arming rotative speed of approximately two thousand revolutions per minute, to arm the element by the centrifugal force developed thereby in the triggers. This force throws them outward, clear of the flange and into the armed position of the element. This position is normally occupied during flight, up to the instant the projectile meets a retarding 40 obstruction. The instant it is retarded, the spool and its attached parts instantly fly to the firing position shown in Fig. 2; strike the pin, 14, and fire the explosive charge, as already described.

45 If, by accident, during transportation or otherwise, the fuse is rotated at a sufficiently high speed to arm the percussion element, the compressive force of the spring will automatically return the several parts forming the element, into their locked and disarmed position immediately after the rotation falls below a predetermined arming speed. This 55 is an important and valuable feature which avoids the great danger from handling an armed fuse or explosive projectile after it has accidentally been rolled down an incline or otherwise rotated above the arming speed.

I claim as my invention and desire to secure by Letters Patent:

60 1. The combination, in an explosive pro-

jectile fuse, of a percussion chamber; a firing pin and a detonator cap oppositely disposed therein; a reciprocating member adapted to explode the cap against the firing pin and having a spring seat formed thereon; means for transmitting a fire flash to a powder charge; centrifugal triggers engaging and locking the reciprocating member in disarmed position; a laterally projecting arm formed on each trigger; means 70 for pivotally supporting and guiding the triggers; a movable spring seat bearing against said arms; and a spring interposed between the seats and exerting centripetal force upon the triggers for holding the reciprocating member in locked and disarmed position until the fuse is rotated, while in flight, above a predetermined arming speed for the purpose of firing an explosive charge.

15 2. The combination, in an explosive projectile fuse, of a percussion chamber; a firing pin and a detonator cap oppositely disposed therein; a reciprocating member adapted to explode the cap against the firing pin; a 75 guiding flange formed on the back end of the reciprocating member; means for transmitting a fire flash from the cap to a powder charge; centrifugal triggers engaging the reciprocating member and locking it in 80 disarmed position; means for pivotally supporting and guiding the triggers; a spring seated upon the flange; and transmitting means interposed between the spring and triggers for exerting centripetal force upon 85 the triggers, for holding the reciprocating member in locked and disarmed position.

3. The combination, in an explosive projectile fuse, of a percussion chamber; a firing pin and a detonator cap oppositely disposed therein; a reciprocating member adapted to explode the cap against the firing pin; means for guiding the reciprocating member; means for transmitting a fire flash from the cap to a powder charge; longitudinally disposed centrifugal triggers engaging the rear end of the reciprocating member and locking it in disarmed position; means for pivotally supporting and guiding the triggers; laterally projecting arms formed on the front ends of the triggers; and a spring opposing the reciprocating member, and bearing against said arms, for exerting centripetal force upon the triggers for holding the reciprocating member in locked and disarmed position.

4. The combination, in an explosive projectile fuse, of a percussion chamber; a firing pin fixed in the front end thereof; a percussion spool disposed within the chamber and adapted to contain a powder core and to slide toward and from the firing pin; a detonator cap carried in the front end of the spool, adjacent to the firing pin; a centrifugal locking trigger disposed within the 100 105 110 115 120 125 130

chamber, adjacent to the spool; means for pivotally supporting and guiding the trigger; and a spring interposed between the spool and trigger, and exerting centripetal force on the trigger whereby it will be held in its inner locked and disarmed position until the fuse is rotated, while in flight, above a predetermined arming speed for the purpose of firing an explosive charge.

5. The combination, in an explosive projectile fuse, of a percussion chamber; a firing pin fixed in the front end thereof; a percussion spool disposed within the chamber and adapted to contain a powder core and to slide toward and from the firing pins; a detonator cap carried in the front end of the spool, adjacent to the firing pin; a plurality of centrifugal locking triggers disposed within the chamber, adjacent to the 20 spool; means for pivotally supporting and guiding the triggers; and a spring interposed between the spool and triggers, and exerting centripetal force on the triggers whereby they will be held in their inner locked and disarmed positions until the fuse is rotated, while in flight, above a predetermined arming speed for the purpose of firing an explosive charge.

6. The combination, in an explosive projectile fuse, of a percussion chamber; a firing pin fixed in the front end thereof; a percussion spool disposed within the chamber and adapted to contain a powder core and to slide toward and from the firing pin; a powder core inclosed within and carried by the spool; fire-flash discharge outlets formed on the spool and chamber; closing disks for covering said outlets; a detonator cap carried in the front end of the spool, in communication with the powder core, and adjacent to the firing pin; a centrifugal locking trigger disposed within the chamber, adjacent to the spool; means for pivotally supporting and guiding the trigger; and a spring interposed between the spool and trigger, and exerting centripetal force on the trigger, whereby it will be held in its inner locked and disarmed position until the fuse is rotated, while in flight, above a predetermined arming speed for the purpose of firing an explosive charge.

7. The combination, in an explosive projectile fuse, of a percussion chamber; a fire flash outlet formed thereon; a firing pin fixed in the front end thereof; a laterally slotted cup inclosed therein; an opening formed centrally in the front end of said cup; a centrally disposed percussion spool, which is guided at its front end by said opening and adapted to slide toward and from the firing pin; a detonator cap carried in the front end of the spool; centrifugal locking triggers disposed in the slots of the cup, each having an arm extending inwardly and radially, relatively to the chamber and

spool; and a spring encircling the spool and adapted to bear on the arms, said spring exerting centripetal force on the triggers whereby they will be held in their inner locked and disarmed positions until the fuse 70 is rotated, while in flight, above a predetermined arming speed for the purpose of firing an explosive shell.

8. The combination, in an explosive projectile fuse, of a percussion chamber; a firing pin fixed in the front end thereof; a percussion spool disposed within the chamber and adapted to contain a powder core and to slide toward and from the firing pin; a detonator cap carried in the front end of 80 the spool, adjacent to the firing pin; an outwardly projecting flange formed on the rear end of the spool; centrifugal locking triggers disposed adjacent to the spool and within the chamber so as to abut against 85 the flange and lock the spool when against the rear end of the chamber; means for pivotally supporting the triggers; and a spring interposed between the spool and triggers and exerting centripetal force on the triggers 90 whereby they will be held in their inner locked and disarmed position until the fuse is rotated, while in flight, above a predetermined arming speed for the purpose of firing an explosive charge.

95

9. The combination, in an explosive projectile fuse, of a percussion chamber; a firing pin fixed in the front end thereof; a percussion spool disposed within the chamber and adapted to contain a powder core 100 and to slide toward and from the firing pin; a detonator cap carried in the front end of the spool, adjacent to the firing pin; centrifugal locking triggers disposed within the chamber adjacent to the spool; means for 105 pivotally supporting and guiding the triggers; and automatic means, interposed between the spool and triggers, and exerting centripetal force, whereby they will be held in their inner locked and disarmed position 110 until the fuse is rotated, while in flight, above a predetermined arming speed for the purpose of firing an explosive charge, and also to automatically return, and lock, the percussion spool in its disarmed position 115 when the rotative speed becomes less than said arming speed.

10. The combination, in an explosive projectile fuse, of a percussion chamber; a firing pin fixed in the front end thereof; a percussion spool disposed within the chamber and adapted to slide toward and from the firing pin; a detonator cap carried in the front end of the spool, adjacent to the firing pin; centrifugal locking triggers having inwardly projecting arms formed thereon, and disposed within the chamber adjacent to the spool; means for pivotally supporting the triggers; a spring interposed between the trigger arms and the spool; and an inter- 130

posed washer adapted to bear on the arms for the purpose of transmitting thereto pressure from the spring.

11. The combination, in an explosive projectile fuse, of a percussion chamber; a firing pin fixed in the front end thereof; a percussion spool disposed within the chamber and adapted to contain a powder charge and to slide toward and from the firing pin;
- 10 a detonator cap carried in the front end of the spool, adjacent to the firing pin; centrifugal locking triggers having inwardly projecting arms formed thereon, and disposed within the chamber adjacent to the spool; means for pivotally supporting the triggers; a spring seat formed on the spool; and a spring encircling the spool, one end thereof abutting against the seat and holding the spool in its normally locked position, and the other end thereof exerting centripetal force on the trigger arms, whereby the triggers will be held in their inner locked and disarmed position until the fuse is rotated, while in flight, above a predetermined
- 20 arming speed for the purpose of firing an explosive charge.

12. The combination, in an explosive projectile fuse, of a percussion chamber; a firing pin fixed in the front end thereof; a percussion spool having a flange formed thereon and disposed centrally within the chamber, and adapted to slide toward and from the firing pin; a detonator cap carried in the front end of the spool, adjacent to the firing pin; a laterally slotted cup disposed 30 within the chamber and encircling the spool; an annular space being disposed between the spool and cup; pivoted centrifugal locking triggers disposed in the slots and having arms protruding from the slots inward into the annular chamber; and a spring disposed in the annular space of the chamber, and interposed between the flange of the spool and the trigger arms, for the purpose of holding the spool and the triggers in 40 their normally disarmed and locked position.

WILLIAM DALTON.
